CLAIM

We claim the ornamental design for a stacking kit for washing machine, as shown and described.

DESCRIPTION

FIG. 1 is a front perspective view of a stacking kit for washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is an enlarged view of the encircled portion in FIG. 1; and,

FIG. 10 is a front perspective view of the stacking kit for washing machine shown in a state of use.

The dash-dash broken lines in FIGS. 1 through 9 show portions of the stacking kit for washing machine which form no part of the claimed design.

The dash-dash broken lines in FIG. 10 depict environmental subject matter and form no part of the claimed design.

The dot-dash broken lines encircling portions of the claimed design that are illustrated in enlargements form no part of the claimed design.

1 Claim, 10 Drawing Sheets
